CHIPPING HAMMER HEAD

Irving V. Hefner, 439 Papworth,
Metairie, La. 70005

Filed Aug. 21, 1967, Ser. No. 8,330

Term of patent 14 years

(Cl. D93—4)

FIG. 1

FIG. 2

FIG. 3

FIG. 4

FIG. 1 is a side view of the chipping hammer head with the handle shown in broken lines;

FIG. 2 is a top view;

FIG. 3 is a view of the serrated design at the blade end which is at the left side of FIGS. 1 and 2, with the handle shown in broken lines; and,

FIG. 4 is a view of the pointed end which is at the right side of FIGS. 1 and 2, with the handle shown in broken lines.

The side shown in FIG. 1 is the left side of the hammer and the right side, not shown, is identical to the view shown in FIG. 1. The portions shown in broken lines are included for illustrative purposes only.

I claim:

The ornamental design for a chipping hammer head, as shown and described.
